GARMENT HANGER

Walter W. Keys, Pittsfield, Mass.

Application August 22, 1946, Serial No. 692,261

8 Claims. (Cl. 223—88)

1

My invention relates to garment hangers and particularly to improvements in trousers hangers and combined coat and trousers hangers.

The principal object of my invention is to provide an improved trousers hanger of the type in which the trousers-engaging means are inserted in the bottoms of the legs and which frictionally engage oppositely disposed portions thereof. More particularly, the objects are to provide a trousers hanger in which the trousers-engaging elements may be readily adjusted and positively locked in various positions to accommodate trousers having bottoms of different widths; to provide, in connection therewith, a means whereby at least one of the trousers-engaging elements may be retracted towards the other element to facilitate the removal and replacement of the trousers on the hanger; and, at the same time, to provide a means for holding the trousers firmly after they have been placed thereon.

I accomplish these objects by means of the novel combination and arrangement of elements described below and illustrated in the accompanying drawing in which:

Fig. 1 is a side elevation view of my hanger; Fig. 2 is an enlarged fragmentary section of Fig. 1 in the plane 2—2;

Fig. 3 is a fragmentary longitudinal section through the lower left half of Fig. 1 to a somewhat enlarged scale;

Fig. 4 is a fragmentary side elevation view of the portion of the hanger shown in section in Fig. 3 but illustrating the trousers-engaging element in retracted position; and

Fig. 5 is an exploded perspective view showing the various elements going to make up my hanger together with a fragmentary portion of the bar upon which they are assembled.

Referring to the drawing:

My hanger comprises an elongated bar 1, preferably rectangular in cross section and provided with two, spaced, transversely-extending slots 2 and 3 therein. If desired, a single long slot may be used and the bar 1 may comprise a portion of a coat hanger 4 provided with a hook 5 as shown in Fig. 1. Preferably, the bar and coat hanger are molded as an integral unit from a suitable plastic material.

The top of the bar 1 at each side of the center thereof and adjacent the slots is provided with a plurality of uniformly spaced cylindrical holes 6 which are adapted to receive a pin 7 for positively locking the trousers-engaging elements in adjusted position, as will be described below.

The trousers-engaging elements 8 are identical

and are formed of wire bent as best shown in Fig. 5. The portions 9 of the elements 8 extend through the slots 2 and 3 and may slide freely therein. Thus, the elements 8 are provided with portions which depend below the bar 3 at each side thereof.

In order to secure the elements 8 to the bar, I provide a pair of side plates 10 having upper flanges 11 and lower flanges 12 adapted respectively to overlie and underlie the top and bottom edges of the bar 1. Between the sections of the flange 11 each of the side plates 10 is provided with an upstanding ear 13 having openings 14 therethrough which are adapted to receive the projections 15 on the lock represented generally by the numeral 16. The lock comprises a flat spring element 17 to which the bent-up plate 18 is secured by the pin 7 which is riveted or otherwise secured thereto as shown at 19. The outer sides of the plates 10 are provided with trunnions 20 which are riveted or otherwise secured thereto as best shown in Fig. 5.

In order to secure all of the parts in assembled relation as shown in Figs. 1 to 4 inclusive, and also to provide a means for retracting the leg-engaging elements 8, I provide a finger lever such as shown at 21. The lever 21 is provided with two parallel disposed, depending branches 22 having openings 23 in the end thereof adapted to receive the trunnions 20 on the side plates 10. The lever 21 is also provided at each side thereof with laterally-projecting, box-like portions 24 having openings 25 in the side walls thereof adapted to pass the ends 26 of the elements 8. It is to be understood that the normal distance between the free ends 26 of the elements 8 and the portions of said elements adjacent thereto, when disassembled, is normally greater than the distance between the outside walls of the boxes 24. Portions 27 at the open ends of the boxes 24 are turned in as shown in Figs. 2, 4 and 5 and are provided with inclined edges 28 as best shown in Fig. 2. Thus, in order to assemble the finger levers 21 and their associated elements 8, the free ends of the elements 8 must be squeezed together and forced upwardly past the turned in portions 27. The side plates 10 are merely positioned against the opposite sides of the bar 1 with the projections 15 on the locking elements 16 positioned in the holes 14 of the elements 10. The depending portions 22 of the finger lever may then be dropped over the side plates and snapped over the trunnions 20, the trunnions 20 being received in the holes 23 in the elements 22. When assembled, the flat

springs 17 of the locking elements will rest on the top surface of the bar 1 with the pins 7 in one of the holes 6.

In operation, the distance between the trousers-engaging portions of the elements 8 may be first adjusted, so that they will engage the insides of the trousers legs firmly, by pressing downwardly on the upturned portions 18 of the locks which will raise the pins 7 from the holes and permit the entire assemblies to be moved along the bar and positively locked in adjusted position by releasing the pressure on the portions 18 so that the pins 7 will be forced downwardly into the proper hole 6 in the bar 1. Preferably, the distance between the trousers-engaging elements 8 is so adjusted that it slightly exceeds the distance across the inside of the bottom of the trousers leg when folded flat. Thus, when the elements 8 are inserted in the trousers leg, they will tend to stretch it slightly and thus engage it firmly. To facilitate inserting the elements 8 in the trousers legs either one or both of the finger levers 21 may be raised to the position shown in Fig. 4 which will reduce the distance between the trousers-engaging elements so that they may be readily inserted in the bottoms of the trousers. Thereafter, the finger levers are pushed downwardly to force the engaging elements 8 into firm contact with the insides of the trousers legs.

It will be readily apparent that where the movement of one only of the trousers-engaging elements by means of its associated lever 21 is sufficient to allow both trousers-engaging elements 8 to be inserted in the trousers, the other element may be fixed. Thus, while I prefer to have both of the engaging elements adjustable, it is only necessary that one of the said elements be adjustable.

What I claim is:

1. A garment hanger comprising an elongated bar, a pair of elements adapted to be inserted in and frictionally to engage the bottoms of a pair of trousers, means for movably mounting each of said elements on said bar to slide towards and away from each other, whereby they may be adjusted along the bar to engage trouser bottoms of different size, means for locking each of said mounting means in adjusted position, and means for retracting each of said elements to facilitate inserting them in said trousers and removing said trousers therefrom.

2. A garment hanger comprising an elongated bar having two, spaced transverse slots therein, a trousers-bottom-engaging element slidably mounted in each of said slots and provided with a depending portion on each side of said bar, means for adjusting and locking said elements in predetermined positions in said slots and in spaced relation to each other on the bar to firmly and frictionally engage the bottoms of a pair of trousers when inserted therein, and means for retracting said elements when locked to facilitate inserting them in said trousers and releasing said trousers therefrom.

3. A garment hanger comprising a coat hanging portion having a hook thereon, and a trousers hanging portion comprising a pair of spaced elements disposed below said coat hanging portion and adapted to be inserted in the bottoms of said trousers, and a lever cooperating with at least one of said elements for moving said one element towards the other element to facilitate the entrance of said elements into the bottoms of said trousers and thereafter moving said one element away from the other element and positively lock-

ing said elements in firm, frictional engagement with the insides of the bottoms of said trousers.

4. A garment hanger comprising an elongated bar, a pair of elements adapted to be inserted in the bottoms of a pair of trousers, means slidably mounted on said bar for securing each of said elements thereto in spaced relation to each other and depending from said bar, means for locking said securing means to said bar in predetermined spaced relation to each other and a lever cooperating with at least one of said elements and its securing means for effecting movements of said one element towards and away from the other of said elements and for positively locking the elements in firm, frictional engagement with the insides of the bottoms of the trousers.

5. In a garment hanger comprising an elongated bar having a longitudinally extending slot therein, the combination with a first trousers-leg-engaging means slidably mounted in said slot and provided with transversely spaced portions depending below said bar, each adapted to be inserted in the bottom of a trouser leg, of a second trousers-leg-engaging means secured to said bar in spaced relation to said first means and comprising depending portions each adapted to be inserted in the bottom of a trousers leg and to cooperate with said first means for suspending said trousers therefrom by frictional engagement with the inside bottoms of said trousers legs, means slidably mounted on said bar and cooperating with said first means for locking the same in various positions on said bar, whereby said hanger may be adjusted to accommodate trousers having bottoms of various size, and means cooperating with said first means and the means slidably mounted on said bar for retracting said first means without unlocking said locking means; whereby to facilitate the placing of said trousers on said hanger and releasing them therefrom.

6. In a trousers hanger of the character described, the combination with an elongated bar, of elements slidably mounted on said bar in spaced relation to each other longitudinally of said bar and adapted to be inserted in and frictionally to engage the inside bottoms of the legs of said trousers to suspend said trousers therefrom, means for adjusting the spacing of said elements to allow trousers having bottoms of different size to be readily slipped thereover, and means for thereafter positively forcing said elements apart and positively locking them in forced-apart relation in firm frictional engagement with the insides of the bottoms of said trousers.

7. In a trousers hanger of the character described comprising an elongated bar provided with an elongated slot extending transversely therethrough, the combination with a trousers-leg-engaging element comprising a wire extending through said slot and having depending portions at each side of said bar adapted to be inserted in the legs of a pair of trousers, of a mounting for said element comprising a pair of side plates partially surrounding said bar, means pivotally mounted in said side plates and cooperating with said bar for locking said plates against movement longitudinally of said bar, and a finger lever pivotally mounted on said side plates and cooperating with said wire to move it back and forth in said slot and also to hold said parts in assembled relation.

8. A garment hanger of the character described comprising an elongated bar, a pair of

trouser engaging elements each having portions for separate frictional engagement within leg bottoms of a pair of trousers, means movably mounting said elements on said bar so as to be slidable towards and away from each other to adjust the elements for engagement within trouser bottoms of different size, means for locking said mounting means in predetermined position of adjustment, and means for producing relative movement of said elements towards and away from each other in the locked position of the mounting means to facilitate inserting the elements in the bottoms of a pair of trousers and removing the trousers therefrom and to expand and lock said elements in frictional supporting 15 engagement with said trouser bottoms.
